V. ANGERER.
RAILROAD CROSSING.
APPLICATION FILED JAN. 24, 1922.

1,428,514.

Patented Sept. 12, 1922.

UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF EASTON, PENNSYLVANIA, A CORPORATION OF PENNSYLVANIA.

RAILROAD CROSSING.

Application filed January 24, 1922. Serial No. 531,408.

To all whom it may concern:

Be it known that I, Victor Angerer, a citizen of the United States, residing at Ridley Park, in the county of Delaware and 5 State of Pennsylvania, have invented certain new and useful Improvements in Railroad Crossings, of which the following is a specification.

This invention relates more particularly 10 to crossings for heavy duty service.

Objects of the invention are to provide crossing castings of greater height than the adjoining rails so as to increase the strength 15 of the crossing and render the same less liable to bend under heavy traffic; to provide interlocking diagonal joints; to provide against wedging action due to creeping; and to provide for properly insulating the crossing in accordance with railroad specifications. 20

Such and other objects, as well as the nature, characteristic features and scope of the invention will more readily be understood 25 from the following description, taken in connection with the accompanying drawings, forming a part hereof, wherein,—

Figure 1 is a plan view of a crossing embodying my invention.

Fig. 2 is a section on line 2—2 of Fig. 1. 30 Fig. 3 is an enlarged broken plan, showing the diagonal joint.

Fig. 4 is a section on line 4—4 of Fig. 3.

Fig. 5. is a section on line 5—5 of Fig. 3.

Fig. 6 is a plan view of a modified form 35 of joint; and

Fig. 7. is a section on line 7—7 of Fig. 6.

The crossing illustrated is a double track construction, each trackway being constituted of four castings 1, which include 40 the usual bearing faces 2, and flangeways 3.

An important feature of the invention is the construction of these castings of greater height than the adjoining rails 4, in order to provide greater strength and resistance 45 to bending under heavy traffic. In order to secure a proper bearing on the ties, notwithstanding this variation in height, the guard extensions 5, ordinarily in one piece with the crossing to provide for the rail connection therewith, are separate castings with 50 integral plate extensions 6, adapted and arranged to underlie the rails 4.

The flangeway fillers 7 between the guard rail extensions and running rails are sepa-

rate elements, and bolts 8 passing through 55 the guard rail extensions, flangeway fillers, and running rails secure all the parts tightly together and thereby strengthen the joints between the running rails and crossing castings. The plate extensions 6, beside affording a flush bearing, also add materially to the strength of the connection. 60

The abutting ends of the crossing members have diagonal faces 9 with tongue and groove formations 10 which provide an effective interlock. 65

The abutting faces 9 are provided with means tending to prevent creeping. For illustrative purposes such is shown in the form of a projection 11 on one face, and a 70 complementary recess 12 in the opposite face, which operate to prevent a wedging action on the joint incident to any creeping movement of the track. Appropriate insulation is indicated at 13. 75

In Figs. 6 and 7, a modification is shown, wherein one of the interlocking elements 14 of the diagonal joint is provided with a boss or trunnion 15, which is afforded a bearing in a corresponding opening 16 in 80 the opposite element 17. The provision of the trunnion mounting is to prevent wedging action due to creeping, as will be understood, but it also simplifies the insulating of the joint. For example, I may employ an 85 insulating member 18 consisting of fiber board pressed to shape and having a tubular extension 19 to accommodate the trunnion. 20 represents insulation exteriorly of the crossing elements. 90

Having described my invention, I claim,—

1. A railroad mated crossing comprising crossing members of greater height than the adjoining rails, and guard extensions to 95 which the running rails are secured, said guard extensions having integral portions which underlie the running rails.

2. A railroad crossing comprising crossing members of greater height than the adjoining rails, and separate guard extensions having plate portions adapted to underlie the running rails, flangeway fillers between said extensions and rails, and means for securing said parts together. 100

3. A railroad crossing comprising crossing members with diagonally disposed abutting faces beyond the points of intersection, 105

interlocking means for securing them with relation to each other, and means for insulating live metal parts.

4. A railroad crossing comprising mated crossing castings having diagonal joints with tongue and groove connections beyond the points of intersection.

5. A railroad crossing having diagonal joints with interlocking provisions beyond the points of intersection, and means for eliminating wedging action due to creeping.

6. A railroad crossing comprising crossing members of greater height than the adjoining rails, and having diagonally disposed abutting faces, means for securing them relatively, and guard rails having integral foot extensions which underlie and raise the running rails.

7. A railroad crossing comprising crossing members having diagonal joints with trunnion mountings.

8. A railroad crossing comprising crossing members whereof the joints are served with trunnion mountings for the purpose and with the result of eliminating wedging 25 action due to creeping.

9. A railroad crossing comprising crossing members having diagonal joints with trunnion mountings, and insulating material shaped to fit the parts, including the 30 trunnions.

10. A railroad crossing comprising groups of mated crossing castings, four castings to the group, said castings being of greater height than the adjoining rails, and 35 having tongue and groove connections, and separate guards having integral base extensions which underlie and raise the running rails.

In testimony whereof I affix my signature. 40

VICTOR ANGERER.
